AIR CONDITIONING METHOD AND APPARATUS FOR PASSENGER CARS

Leo L. Lewis, Plainfield, N. J., assignor, by mesne assignments, to Carrier Corporation, Newark, N. J., a corporation of Delaware

Application January 12, 1933, Serial No. 651,287

14 Claims. (Cl. 62—117)

This invention relates to methods of and means for conditioning the atmospheres of railroad cars, and more particularly to a system in which a central refrigeration or air conditioning device 5 is adapted to serve a plurality of conditioning equipments located in individual cars remote from said device.

It is a well known fact that railroad cars parked in yards are uncomfortably hot inside 10 during the summer months. This is especially true with reference to the present standard steel car, and passengers entering said cars, at stations, awaiting the starting of the train, are extremely uncomfortable by reason of the high 15 temperature.

The primary object of my invention is to regulate the temperature of parked cars so that passengers may remain in the car with comfort while awaiting the starting of the train.

Another object of my invention is to provide 20 means, whereby the temperature of all cars on the train while en route, may be regulated to the desired temperature.

A further object of my invention is to so 25 arrange an air conditioning system on an individual car so that it may be supplied with a conditioning fluid either from a source within the railroad station or from a source located on the train.

Another object of my invention is to condition 30 the air entering a car (parked and en route), freeing the air from dust, soot, cinders and other foreign matter, controlling its temperature and humidity, and introducing such conditioned air 35 into the car without objectionable drafts.

For purposes of illustrating my invention, I have selected one of many embodiments adapted 40 for carrying out my invention, but I do not wish to be confined to the embodiment shown, in which:

Fig. 1 is a plan view, in outline, of what I shall hereinafter term "the master car", embodying my invention,

Fig. 2 is a similar view of a passenger car 45 adapted to cooperate with the master car,

Fig. 3 is a diagrammatic view of a railroad train, comprising a locomotive, a master car, and several passenger cars, showing practical adaptation of the invention, and

Fig. 4 is a fragmentary elevation of the master car showing a detailed arrangement of the equipment in Fig. 1, with parts operably interpositioned.

My present invention contemplates that water,

or other suitable media, will be chilled to a desired degree within the master car and be distributed to the passenger cars wherein it may be utilized to cool and condition the air therein. Preferably, the master car is located in the forward part of the train adjacent the locomotive, but under certain conditions, it may be located at any other point. Further, my invention contemplates the use of chilled water, or other refrigerant or medium, from any source within the railroad station, while the train is parked, the water being delivered to the cars through conduits similar to those used for supplying steam for heating. In fact, the usual car steam lines may be used under summer operating conditions 15 for transmission of chilled water or other conditioning medium.

With reference to the drawings, similar designations referring to similar parts, numeral 5 designates the master car, in which an electric 20 generator 6 is located. This generator may be driven by a suitable device 7, such as a motor, internal combustion engine or a turbine supplied with steam from the locomotive of the train. This generator will supply the electrical energy 25 necessary to drive the pumps, fans and other elements of the air conditioning equipment.

A refrigerating machine, generally designated by the numeral 8, is located within the master 30 car. Preferably, the machine 8 comprises a centrifugal compressor 9, although any other type could be utilized, driven by an electric motor or steam turbine 10. An evaporator 11 and a condenser 12, cooperate with the compressor to give the desired refrigerating effect. The refrigerant, such as dichloromethane, is compressed by compressor 9 and discharged within condenser 12. Water, circulating in pipes within the condenser, abstracts heat from and thereby causes condensation of the refrigerant. The liquid refrigerant is then delivered to the evaporator 11 wherein it is vaporized to cool a medium such as water or brine flowing through pipes located within the evaporator. The 40 vaporized refrigerant is withdrawn from the evaporator by compressor 9 and the cycle repeated.

The heated water, after passing through the condenser 12, is discharged through pipe 13 and spray heads 14 (Fig. 4) into a cooling tower 15 50 in the form of a fine mist or spray. Cooling tower 15 comprises a casing 16 having an air inlet 17, a motor driven fan 18 and an air discharge 19. The fan 18 draws air from outside the master car through inlet 17, through the 55

sprays and discharges the air through outlet 19 to the atmosphere. In passing through the sprays, the air absorbs a portion of the water, and, as is well understood, cools the remaining portion to a temperature approximating the wet bulb temperature of the incoming air. The cooled water is withdrawn from the tower and discharged by pump 20 through condenser 12 for the purpose of causing refrigerant to condense as hereinbefore explained. To replace the condenser water lost through evaporation in the cooling tower, a reserve supply is maintained in a tank 21 which, for convenience, may be located below the floor of the car. Pipe 22, or valve 23, provide means whereby this supply may be drawn upon by pump 20 when necessary. In the same manner, this make-up water may be drawn from the tender.

1 The chilled water, or brine, is taken from the evaporator 11 by pump 24 and delivered through a suitably insulated pipe 25 extending the length of the train, suitable flexible couplings, similar to the present steam and air connections, being provided between the various cars of the train.

25 Taps or supplemental conduits lead from this cooling medium conveyor line 25 to coolers 26 on each car 27 in the train. A suitable return line 28 is provided for returning the cooling medium from the various coolers 26, to the evaporator 11, in which the water may be rechilled for reuse.

Referring to Fig. 2, each car 27 is provided with a cooler 26, located within a chamber 29. A duct 30, having air inlets 31 communicating with the passenger space, connects at its opposite ends 32 with air inlet chamber 33. Ventilators 34 provide means whereby air from outdoors may be admitted to duct 30 for mixture with air from the passenger space prior to cooling by coils 26. Filters 35 of any desired type, are mounted in the duct ends 32 for removing all foreign matter from air passing therethrough. Centrifugal fans 36 are adapted to draw air through the filter and through openings 31, through the coolers and discharge the air through ducts 37 into the passenger space. This air conditioning, filtering and circulating mechanism in each car may be operated and controlled in accordance with the disclosure in my copending application, Serial No. 598,657 filed March 14, 1932.

By arranging the air conditioning equipment on each car as an individual unit, and by providing fluid supply and return lines common to all the units, it is apparent that applicant has provided a complete system which may be supplied with cooling fluid either from a master car while the train is in motion or from some central source of supply while the train is parked; the lines 25 and 28 being suitably arranged for connection to either source.

It is obvious that instead of using a centrifugal or reciprocating compressor, a steam ejector or jet pump apparatus may be provided as a source of supply for furnishing refrigerated cooling medium to one or a series of cars. Furthermore, if desired, as for short runs, a source of refrigerated fluid may be provided in a tank on the tender or otherwise, from which the fluid cooling medium may be distributed for use in the air conditioning apparatus on individual cars.

Within the scope of my invention, as set forth in the appended claims, the arrangement, construction and operation of the means on the master car or equipment externally of and auxil-

iary to the passenger car or cars to be cooled may be varied to wide degrees from the present disclosure; also, changes in the construction, arrangement and operation of the parts throughout may be resorted to within the scope of such claims without departing from the spirit or sacrificing any of the advantages of the invention.

What I claim is:

1. The method of conditioning air for a passenger car train which consists in chilling a cooling fluid in a master car and conducting said fluid by means of conduits from the master car to the passenger cars in the train, shunting the fluid from said conduits to a cooler in each passenger car in the train, and drawing the air to be cooled over said cooler and discharging said cooled air into the car.

2. The method of treating air for a passenger car train which consists in chilling water, conducting said water through a conduit to the several cars in the train, shunting said water from said conduit into each car in the train, passing said water through a cooler in the car, drawing outside air into each car, filtering said outside air and passing it over said cooler, and then introducing the cooled air into the said car.

3. In combination in a railroad passenger train, a master car, and a plurality of passenger cars, a water chilling equipment in said master car, main conduits connecting said equipment with the passenger cars, to carry the chilled water to the passenger cars, a duct in each of the passenger cars to conduct outside air into the passenger cars, an air filter in said duct, a cooler in said duct, a supplemental conduit leading from the main conduits into said duct to carry the water to said coolers and air ducts in the car, and means for driving the cooled air into the interior of the car.

4. In combination, in an air cooling device for passenger cars, a water chilling equipment, a conduit for the chilled water leading from said equipment, and a supplemental conduit leading from said conduit into a car, a cooler in the car connected with said supplemental conduit, means to pass air over said cooler, and discharge the air from the said cooler into the car.

5. In combination, in a passenger train, a master car, and passenger cars, a water chilling equipment in the master car, main pipes connecting said equipment with the passenger cars, to conduct the chilled water thereto, a cooler in each passenger car, a pipe connecting the cooler to said main pipes, air ducts leading to said cooler, ducts from said cooler to convey the cooled air from the cooler into the car, and means to return the water to the master car.

6. In combination, in a passenger train, a master car, and passenger cars, a water chilling equipment in the master car, main pipes connecting the said equipment with the passenger cars to conduct chilled water thereto, a cooler in each passenger car, a connection between the said main pipe to conduct the chilled water to said cooler, air ducts leading from the exterior of the passenger car to said cooler, and ducts to distribute the air from said cooler into the car.

7. In combination, in a passenger train, a master car, and passenger cars, a water chilling equipment on said master car, main pipes connecting said equipment with the passenger cars, to conduct the chilled water thereto, a cooler in each passenger car, a connection between said main pipe and cooler to conduct the chilled water to said cooler, air ducts leading from the exterior

and interior of the passenger car to said cooler, and ducts to distribute the cooled air from said cooler into the car.

8. In combination, in a passenger train, a master car, and passenger cars, a water chilling equipment on said master car, main pipes connecting said equipment with the passenger cars, to conduct the chilled water thereto, a cooler in each passenger car, a connection between said main pipe and cooler to conduct the chilled water to said cooler, air ducts leading from the exterior and interior of the passenger car to said cooler, and ducts to distribute the cooled air from said cooler into the car and a return water pipe from the passenger cars to the chilling equipment in the master car.

9. In combination, in a passenger train, a master car, and passenger cars, a water chilling equipment on said master car, main pipes connecting said equipment with the passenger cars, to conduct the chilled water thereto, a cooler in each passenger car, a connection between said main pipe and cooler to conduct the chilled water to said cooler, air ducts leading from the exterior and interior of the passenger car to said cooler, and ducts to distribute the cooled air from said cooler into the car and an air filter to free the air from foreign matter before it passes over the cooler.

10. In combination, in a passenger train, a master car, and passenger cars, a water chilling equipment on said master car, main pipes connecting said equipment with the passenger cars, to conduct the chilled water thereto, a cooler in each passenger car, a connection between said main pipe and cooler to conduct the chilled water to said cooler, air ducts leading from the exterior and interior of the passenger car to said cooler, and ducts to distribute the cooled air from said cooler into the car, and a return water pipe from the passenger cars to the chilling equipment in the master car, and an air filter to free the air from foreign matter before it passes over said cooler.

11. The method of conditioning the air in the passenger compartments of cars of a railway train, which consists in cooling a cooling medium at a central point on a train of cars, conducting this cooling medium to cars in a train through a conduit, shunting the said medium from said conduit into a cooling chamber in each car in the train and utilizing the same to cool a surface cooler therein, bringing air into contact with said cooler in said chamber and thereby cooling the same, and discharging the cooled air from said chamber into the passenger compartment of the car.

12. The method of conditioning the air within a railroad car forming part of a train which consists in conditioning a fluid in a master car and conducting said fluid by means of conduits from the master car to said car to be conditioned, shunting the fluid from said conduits to an air conditioning apparatus in said car, and circulating air to be conditioned through said apparatus and then discharging said air into the car.

13. In combination, in an air conditioning system for railway cars, a fluid conditioning equipment located in a master car, a conduit for the fluid leading from said equipment, and a supplemental conduit leading from said conduit into a railway car to be conditioned, an air conditioning apparatus in said railway car connected with said supplemental conduit, means to pass air through said air conditioning apparatus and discharge the air from said air conditioning apparatus into said railway car.

14. The method of conditioning the air within a railroad car forming part of a train which consists in conditioning fluid at a central point adapted to serve one or more cars in such train and conducting said fluid by means of conduits from the central point to a car to be conditioned, shunting the fluid from said conduits to an air conditioning apparatus in said car and circulating air to be conditioned through said apparatus and then discharging said air into said car.

LEO L. LEWIS.
